UNITED STATES PATENT OFFICE.

SAMUEL H. RANSOM, OF ALBANY, N. Y.

DESIGN FOR THE PLATES OF A COOKING-STOVE.

Specification forming part of Design No. 6,728, dated June 24, 1873; application filed April 18, 1873.

To all whom it may concern:

Be it known that I, S. H. RANSOM, of the city and county of Albany and State of New York, having invented a Design for the Plates of a Cook-Stove, of which the following is a specification:

The nature of my design is fully represented in the accompanying engraving, to which reference is made.

A A B represent center ornament for doors—a combination of bulb-shaped raised center, on the surface of which is a raised fancy letter, C, and surrounded by a simple molding, and finished at top and bottom, and on each side, by scroll-work. C represents the ornamentation of the outer edge or frame of the panel

of door, the outer line of it being a series of crescent formations, their ends resting on a straight raised bar. Between these crescents and the straight bar are inserted small bead. D represents the ornamentation in center of closet-door—a combination of a center rosette of eight leaves surrounded by combined shell and scroll-work.

The moldings of the doors and main part of stove I do not claim.

What I claim as my invention is—

A design for the plates of a cook-stove, substantially in the manner above mentioned.
